MERTON H. HAMMETT, OF DAVENPORT, IOWA, ASSIGNOR TO THE BETTENDORF COMPANY, OF BETTENDORF, IOWA, A CORPORATION OF IOWA

SIDE FRAME

Application filed November 7, 1930. Serial No. 493,997.

This invention relates to railway car trucks, and more particularly to the construction of the side frames therefor.

One of the objects of the present invention is to provide a railway car truck side frame of new and improved construction which will materially strengthen and reinforce the spring supporting portion and minimize distortion or deflection thereof under heavy loads.

Another object is to provide a car truck side frame with extension webs, so placed as to minimize deflection of the spring supporting portion and so placed that no excessive mass of metal is formed to cause foundry trouble such as poor metal, shrinkage cracks, and difficulty in removing cores.

Another object is to provide a car truck side frame with reinforcing members in the region of greatest strain in the application of heavy loads without materially increasing the weight of the side frame.

A further object is to provide an improved car truck side frame having top and bottom webs in the spring supporting portion with inclined webs at the sides of and extending upwardly from the upper web of the spring supporting portion toward the bolster columns and merging into the walls of the side frame, and with diagonal tension webs connecting the top and bottom webs of the spring supporting portion between the side walls of the side frame.

A still further object is to provide an improved car truck side frame having vertical struts between the top and bottom webs of the spring supporting portion which, in conjunction with diagonal reinforcing webs, form an inverted queen post truss in the spring supporting portion of the side frame, and which is materially strengthened by means of diagonal webs which extend upwardly from the sides of the top web and merge into the column portions of the side frame.

With the above and other objects in view which will be apparent from the detailed description to follow, the present invention consists in certain features of construction and combinations of parts that will be readily apparent to those skilled in the art to which the invention appertains.

In the drawing which illustrates a suitable embodiment of the present invention,

Fig. 1 is a fragmentary side elevation of a railway car truck side frame, a portion of the spring supporting portion and tension chord being broken away to show a reinforcing web;

Fig. 2 is a vertical section taken substantially on the line 2—2 of Fig. 1;

Fig. 3 is a bottom plan view of the side frame shown in Fig. 1;

Fig. 4 is a section taken substantially on the line 4—4 of Fig. 1 showing the diagonal web and also showing the webs which extend from the upper web of the spring supporting portion and which merge into the side walls of the side frame; and

Fig. 5 is a section taken substantially on the line 5—5 of Fig. 1 showing the web which connects the lower edges of the side walls of the tension chord together.

Referring to the accompanying drawing in which like numerals refer to like parts throughout the several views, the railway car truck side frame of the present invention is preferably in the form of a single piece casting. The side frame is so constructed as to include a compression chord A, a tension chord embodying a central horizontal spring supporting portion B spaced from the compression chord A, and inclined end portions C extending upwardly toward the ends of the compression chord A, and spaced bolster columns D extending upwardly from the ends of the central portion B to the compression chord A. The spaced bolster columns D provide a suitable opening E for the recep-

tion of the ends of the car truck bolsters (not shown).

The compression chord A in section is of inverted channel shape and embodies spaced sides 1 and an interconnecting web 2, and in a similar manner the inclined portions C of the tension chord are formed of spaced sides 3 and webs 4 integrally connecting the lower edges of the sides 3 to provide an upwardly presenting channel-shaped cross section as shown in Fig. 5. The bolster columns D are also channel-shaped in cross section and each includes sides 5 integral with the sides 1 and 3 of the tension and compression chords, respectively, and a web 6 extending transversely of the side frames and interconnecting the edges of the bolster columns adjacent the central bolster opening E. As shown in Fig. 1, the edges of the metal defining the triangular openings formed by the inclined tension chords C, the compression chord A and the bolster columns D is provided with a continuous narrow flange 6a which assists in reinforcing the side frames.

The spring supporting portion B of the tension chord is provided with spaced sides 7 integral with the sides 3 of the inclined portions C and with a bottom web 8 integrally connecting the lower edges of the sides 7. The horizontal portion B is also provided with an upper horizontal web 9 integrally connecting the upper edges of the sides 7 and extending between and merging into the transverse webs 6 of the bolster columns D. The flat upper web 9 extends laterally beyond the sides 7 of the central portion B to form horizontal side flanges 10 which provide a relatively wide spring support immediately beneath the ends of the bolster to be supported within the bolster opening E. The flanges 10 are reinforced by vertical webs 11 which connect the under sides of the flanges 10 with the outer surfaces of the vertical sides 7 of the spring supporting portion B.

The flat upper web 9 extends from the base of one bolster column B to the base of the other bolster column, so that a relatively wide and a relatively long flat spring supporting portion is provided between the bolster columns, which permits the use of a relatively large number of bolster supporting springs and gives an increased distance along the center line of the spring supporting portion for the placing of such springs in any desired group.

In order to effectively strengthen the tension chord, reinforcing webs 12 have been provided to extend diagonally across the lower corners of the bolster receiving opening E. These webs are formed with outer portions forming continuations of the flanges 10 which merge into the flanges 10 at points inwardly of the columns D and extend upwardly from the flanges 10 and merge into

the side walls of the side frames at a point beyond the junctures of the upper flat web 9 with the transverse webs 6 of the bolster columns, and with inner portions curved inwardly, as shown in Fig. 2, which merge into the inner faces of the transverse webs 6 of the bolster columns substantially.

It will be seen therefore that due to the provision of the webs 12 a very long spring seat may be obtained substantially along the longitudinal center line of the side frame, and a relatively wide seat may be obtained along the transverse center line, without any sacrifice in strength of the spring supporting portion.

Spaced vertical struts 13 are provided between the sides 7 of the spring supporting portion B which extend from the lower transverse web 8 to the upper web 9. These spaced struts 13, as shown in Figs. 1 and 2, are approximately of the same thickness as, and are preferably arranged in parallel relationship with respect to, the side walls 7.

The webs 4 of the inclined tension chord portions C are provided with triangular recesses 14 directly below the bolster columns D. The recesses 14 form flanged portions 14a integral with the web 4 which diverge in decreasing width toward the lower horizontal web 8 of the central portion D, and merge into the web 8 substantially in the region of the vertical struts 13.

In order to further materially strengthen the spring supporting portion, a tension member 16 is provided at each end of the lower web 8 and is so placed that it is necessary for it to elongate before any deflection of the spring supporting portion can occur. This added tension member is in the form of a web which extends diagonally upwardly from substantially the connection of the vertical struts 13 with the lower web 8 and merges into the upper web 9 in the region of the connections of the transverse webs 6 of the bolster columns with the flat upper web 9.

If desired, each web 16 directly below the upper horizontal web 9 may be centrally recessed at 17, as shown directly below the web 9, thus providing spaced leg portions joining in with the sides 7 of the spring supporting portion.

It will thus be seen that I have provided a tension chord comprising the central portion B and inclined portions C, with reinforcing webs 16 which extend upwardly at an angle from the lower horizontal web 8 and merge into the connections between the upper horizontal web 9 and the transverse webs 6 of the vertical bolster columns D.

It will further be seen that I have provided each inclined portion C of the tension chord with webs 4 which terminate in flanges 14a that extend downwardly to a horizontal position and then merge into the bottom web 8 substantially at the sides 7 in the region of

the integral connections between the vertical reinforcing struts 13, lower horizontal web 8, and reinforcing web 16.

It will also be seen that I have provided reinforcing members 12 extending from the side flanges 10 upwardly at an angle across the corners of the bolster opening and merging into the sides of the column D beyond the transverse webs 6 of the bolster columns 10 and also merging into the inner faces of the transverse webs 6.

The reinforcing web 16 provides an added tension member for the tension chord comprising the portions B and C which is so placed that it is necessary for it to elongate before any deflection of the spring supporting portion can occur. In other words, the spring supporting portion is provided with vertical reinforcing struts 13 which connect the upper and lower webs 8 and 9, respectively, and with inclined webs 16 which extend from the intersections of the struts 13 with the web 8 and merge into the ends of the upper web 9 substantially in the region 25 of the transverse webs of the bolster columns therewith. This in effect provides a bridge truss action which, in combination with the flange portions 14a of the webs 4 that connect into the horizontal web 8 and with the 30 inclined webs 12 extending across the corners of the bolster opening, provides reinforcing means arranged in the region where the greatest strain comes in the application of heavy loads, without materially affecting the weight 35 of the side frame.

The load carried on the spring supporting portion is transmitted to the inclined reinforcing web 16 at the flange portion 14a so that greatly added strength is supplied at the 40 regions where the greatest distortion would otherwise occur, thereby minimizing distortion and deflection of the spring supporting portion, and strengthening the side frame at this point. This truss action places the web 45 9 and vertical struts 13 in compression, and the lower webs 8 and inclined webs 16 in tension, thus, as just described, providing a well reinforced tension chord which prevents substantial distortion and deflection of the 50 spring supporting portion under the application of heavy loads.

It has been found by forming the apertures in the webs 4 and the diagonal reinforcing webs 16 that the weight thereof is reduced 55 without impairing the strength, and that the manufacture thereof is materially facilitated by reducing cooling strains. These apertures also add to the ease with which the cores used in the casting operation may be removed.

60 In the side frame structure shown and described, it will be observed that the reinforcing webs and tension chords are so constructed as to permit the spring supporting portions, bolster webs and reinforcing webs 65 to merge without forming excessive metal at

the point of merging, and yet give the necessary strength. This is a very advantageous feature in that it eliminates foundry trouble and provides for fine grained satisfactory metal which is free from shrink pockets, 70 pipes, and shrinkage cracks.

Aside from the specific embodiments of the invention herein shown and described, it will be understood that numerous details of the construction may be altered or omitted without departing from the spirit and scope of the invention, and I do not desire to limit the invention to the exact construction shown as I desire to claim the invention broadly as well as specifically as indicated in the appended 75 claims.

What I claim is:

1. A one-piece car truck side frame comprising a compression chord, a tension chord, and spaced bolster columns extending vertically between said compression and tension chords, said tension chord having a central horizontal spring supporting portion including an upper web joined at its ends with said bolster column, extension flanges on said web extending beyond the sides of said frame, each flange having continuation webs at its ends extending upwardly at an angle in gradually decreasing width and merging into the sides of said bolster columns outwardly of the transverse edges thereof, a lower web spaced from said upper web, and inclined webs extending from said lower web and joined with said upper web in the region of the connections of said upper web with said 85 bolster columns. 90

2. A one-piece car truck side frame comprising a compression chord, a tension chord, and spaced bolster columns extending vertically between said compression and tension chords, said bolster columns including spaced sides and a transverse web integrally connecting said sides at their inner edges, said tension chord having a central horizontal 105 spring supporting portion including spaced sides, an upper web joined at its ends with said bolster columns and at its side edges with said last mentioned spaced sides, extension flanges on said upper web extending outwardly beyond said sides, continuation webs 110 integral with said flanges extending upwardly at an angle and merging into the sides of said bolster columns outwardly of the transverse webs, a lower web spaced from said upper web and joined at its side edges with said spaced sides, and inclined webs integral with and extending from said lower web and joining with said upper web in the region of the connections of said bolster columns with said upper web, said inclined webs being integral with the sides of said spring supporting portion. 115

3. A one-piece car truck side frame comprising a compression chord, a tension chord, and spaced bolster columns extending ver- 130

5 tically between said compression and tension chords, said bolster columns including spaced sides and a transverse web integrally connecting said side at their inner edges, said 10 tension chord having a central horizontal spring supporting portion including spaced sides, an upper web joined at its ends with said bolster columns and at its side edges with said last mentioned spaced sides, extension 15 flanges on said upper web extending outwardly beyond said spaced sides, continuation webs integral with said flanges extending upwardly at an angle and merging into the sides of said bolster columns outwardly of the 20 transverse webs, said continuation webs also merging into the transverse webs of said bolster columns, a lower web spaced from said upper web and joined at its side edges with said spaced sides, and inclined webs integral 25 with and extending from said lower web and joining with said upper web in the region of the connections of said bolster columns with said upper web, said inclined webs being integral with the sides of said 30 spring supporting portion.

4. A one-piece car truck side frame comprising a compression chord, a tension chord and spaced bolster columns extending vertically between said compression and tension 35 chords and forming a bolster opening therebetween, said tension chord having a central horizontal spring supporting portion including spaced sides, upper and lower webs extending horizontally between said sides, said 40 upper web being integral with and extending from the base of one bolster column to the base of the other bolster column and also extending transversely beyond said spaced sides to form overhanging flanges, inclined 45 webs extending from said lower web and merging into said upper web in the region of the connections of said bolster columns therewith, and reinforcing webs extending 50 diagonally across the corners of said bolster opening, said reinforcing webs merging into said overhanging flanges inwardly of said bolster columns and into the walls of said 55 bolster columns outwardly of said bolster opening, said reinforcing webs also merging into the transverse faces of said bolster columns.

5. A one-piece car truck side frame comprising a compression chord, a tension chord and spaced bolster columns extending vertically between said compression and tension 60 chords and forming a bolster opening

65 therewith, said tension chord having a central horizontal spring supporting portion including spaced sides, upper and lower webs extending horizontally between said sides, said upper web being integral with and extending from the base of one bolster column to the base of the other bolster column and also extending transversely beyond said spaced sides to form overhanging flanges, inclined webs extending from said 70 lower web and merging into said upper web

75 in the region of the connections of said bolster columns therewith, and reinforcing webs extending diagonally across the corners of said bolster opening, said reinforcing webs merging into said overhanging flanges inwardly of said bolster columns and into the walls of said bolster columns outwardly of said bolster opening, said reinforcing webs also merging into the transverse faces of said bolster columns.

6. A one-piece car truck side frame comprising a compression chord, a tension chord, and spaced bolster columns extending vertically between said compression and tension chords, said tension chord having a central horizontal spring supporting portion including an upper web joined at its ends with said bolster column, extension flanges on said web extending beyond the 80 sides of said frame, each flange having continuation webs at its ends extending upwardly at an angle in gradually decreasing width and merging into the sides of said bolster columns outwardly of the transverse edges thereof, a lower web spaced from said 85 upper web, spaced vertical struts extending between said upper and lower webs, and inclined webs extending from said lower web and joined with said upper web in the region of the connections of said upper web with 90 said bolster columns.

7. A one-piece car truck side frame comprising a compression chord, a tension chord, and spaced bolster columns extending vertically between said compression and tension chords, said tension chord having a central horizontal spring supporting portion including an upper web joined at its ends with said bolster column, extension flanges on said web extending beyond the 95 sides of said frame, each flange having continuation webs at its ends extending upwardly at an angle in gradually decreasing width and merging into the sides of said bolster columns outwardly of the transverse edges thereof, a lower web spaced from said 100 upper web, spaced vertical struts extending between said upper and lower webs, said vertical struts being spaced from the sides of said 105 spring supporting portion and inclined webs extending from said lower web and joined with said upper web in the region of the connections of said upper web with said bolster columns.

8. A one-piece car truck side frame comprising a compression chord, a tension chord, and spaced bolster columns extending vertically between said compression and tension chords, said tension chord having a central horizontal spring supporting portion including an upper web joined at its ends with said bolster column, extension flanges on said web extending beyond the 110 sides of said frame, each flange having continuation webs at its ends extending upward-

ly at an angle in gradually decreasing width and merging into the sides of said bolster columns outwardly of the transverse edges thereof, a lower web spaced from said upper web, spaced vertical struts extending between said upper and lower webs, and inclined webs extending from said lower web and joined with said upper web in the region of the connections of said upper web with said bolster columns, said continuation webs also merging into the transverse webs of said bolster columns.

In testimony whereof I affix my signature.
MERTON H. HAMMETT.
